UNITED STATES PATENT OFFICE.

CLARENCE E. KLING, OF HARRISBURG, PENNSYLVANIA.

RAILWAY-SWITCH.

No. 799,738.

Specification of Letters Patent.

Patented Sept. 19, 1905.

Application filed December 2, 1904. Serial No. 235,189.

To all whom it may concern:

Be it known that I, CLARENCE E. KLING, a citizen of the United States, and a resident of Harrisburg, in the county of Dauphin and State of Pennsylvania, have invented a new and Improved Railway-Switch, of which the following is a full, clear, and exact description.

The purpose of the invention is to provide 10 a construction of railway-switch in which the main line is always open and wherein when it is desired to pass to a siding the switch can be set from the engine-cab and locked in such position until the entire train has passed upon 15 the siding, whereupon the switch will be automatically returned to its position for the main line, the operation being the same when a train is to pass from a siding to the main line, with the exception that the operation at 20 such time is entirely automatic.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a diagrammatic plan view of the 30 improved switch mechanism. Fig. 2 is a side elevation of the outer rail of the siding, showing the parts in position for a train to pass therefrom on to the main track. Fig. 2^a is a continuation of Fig. 2, showing the outer siding-rail where it connects with the corresponding main rail and a portion of the latter. Figs. 3 and 3^a are views similar to Figs. 2 and 2^a, but showing the positions of the parts of the switch when a train has entered upon a 35 siding or is passing to the main track. Figs. 4 and 4^a are views similar to Figs. 3 and 3^a, illustrating the positions of the parts when the train is about to pass from the siding to the main track. Fig. 5 is a horizontal section through the rails and connections shown in Fig. 4, and Fig. 5^a is a horizontal section through the rails and connected parts shown in Fig. 4^a. Fig. 6 is a side elevation of a part of the main rail from the opposite side of the 45 track and showing the positions of the parts when a train is to pass from the main track to the siding. Fig. 6^a is a continuation of Fig. 6, showing the position of the parts of the switch at the siding, the track being viewed 50 from the same direction as in Fig. 6. Fig. 7 is a plan view of the parts shown in Fig. 6,

and Fig. 7^a is a plan view of the parts shown in Fig. 6^a.

A represents a portion of the main track, the rails whereof are designated as 10 and 11. 60

B represents a siding which connects with the main track, the rails of the siding being designated as 12 and 13.

C represents the switch-points, which are shown in position to leave the main track 65 open.

C' represents the bridge-rail in the main track leading to the siding, and C^a the fixed point or frog which is usually employed in connection with a bridge-rail. 70

At the right-hand side of the main track A, adjacent to the outer rail 11 and at any desired distance from the switch-points C, a lever 14 is fulcrumed, usually at its center, by means of a suitable pin 15, properly supported, as is shown in Figs. 1 and 7, and a connecting-rod 16 is pivoted to the outer end of the lever 14 and is likewise pivoted to an elbow-lever 17, suitably fulcrumed at a point adjacent to the said rail 11 of the main track. 80 This elbow-lever 17 is connected by a link 18 with a second elbow-lever 19, as is also shown in Figs. 1 and 7.

At the right-hand side of the main track A, at that part where the switch-points C are located, a rocking plate 20 is fulcrumed at or about the center, and the said rocking plate adjacent to what may be termed its "inner end" is provided with a stud 21, which extends upward from the plate, and when the 90 stud 21 is in operative position, to be herein-after described, said stud is brought opposite a peripherally-grooved and horizontally-mounted friction-roller 22, which occupies a position between the inner edge of the rocking plate 20 and the outer face of the outer rail 11 of the main track A. The elbow-lever 19 is connected with an outer end portion of the rocking plate 20 through the medium of a connecting-rod 23, and a second connecting-rod 24 is attached to the outer end of the said rocking plate 20 opposite the point of connection of the connecting-rod 23. The said connecting-rod 24 is also pivotally attached to an elbow or bell-crank lever 25, which is 100 opposite that portion of the main track which is opposite that portion of the siding B that connects with the said main track, and another connecting-rod 26 is pivotally attached to the elbow-lever 25. This latter connecting-rod 26, as is shown in Fig. 1 and partially 110 so in Fig. 7^a, extends beneath the rails of the

- main track and the rails of the siding to a connection with an elbow-lever 27, which is suitably pivoted adjacent to the outer rail 13 of the siding B, as is shown in Figs. 1 and 5.
- 5 An arched trip-lever D is located at the right-hand side of the main track A or at the outer face of the rail 11 of said track, as is best indicated in Fig. 1 and, as is shown particularly in Fig. 6, this arched trip-lever D 10 consists of two links 28 and 28^a, the link 28 being preferably shorter than the link 28. The link 28^a is nearest the operating-lever 14 and is pivoted, by means of a suitable pin 29, to the outer face of the said main rail 11, and 15 the two links 28 and 28^a are pivotally connected by a pin 30. The link 28, which extends in direction of the switch, is provided at its free end with a longitudinal slot 31, and a pin 32 is passed through this slot 31 into the 20 outer face of the main rail 11, as is shown in said Figs. 1 and 6, so that the members of the arched trip-lever D may be carried down straight or parallel with the rails adjacent to which they are located.
- 25 A connecting-rod 33 is attached to the free end of the link 28, and this connecting-rod is attached to one end of a slide 34, held for movement in a housing 35, suitably supported adjacent to the said rail 11, as is shown in 30 Figs. 1 and 7. This slide 34 is in two members a and a', the member a being that which is attached to the connecting-rod 33. In conjunction with the member a' of the said slide 34 a connecting-bar is employed, constructed 35 in two pivotally-connecting sections 36 and 37, (best shown in Fig. 1,) the two sections being connected by a pivot-pin 38. The section 36 of this divided connecting-bar is pivotally attached to the member a' of the slide 34, 40 while the other member 37 of the same connecting-bar is pivotally attached to a bell-crank lever 39, pivoted upon a suitable support adjacent to the main rail 11, where the switch-points C are located, as also best shown 45 in Fig. 1. The membered connecting-bar thus described passes between the stud 21 on the rocking or revoluble plate 20 and the aforesaid grooved guide-pulley 22, and when the members of this divided and pivotally- 50 united connecting-rod are straightened the action is brought about by the rocking of the said plate 20 in a manner which will bring the stud 21 of the plate against the member 37 of the said connecting-rod and will carry 55 the said member to an engagement with the grooved surface of the friction-pulley 22, as is shown in Fig. 7^a. At such time the two sections a and a' of the slide 34 are made to abut, or practically so, as is shown in Fig. 7, 60 and when the members 36 and 37 of the divided connecting-rod are at angles to each other, as shown in Fig. 1, the members of the arched trip-lever D may be carried down parallel with the rail 11 without interfering

with the section a' of the slide. In fact, dividing the slide 34 admits of lost motion at the arched lever-trip D for a purpose to be hereinafter set forth.

The switch-points C are suitably pivoted and are attached to a shifting or switch bar 40, which extends beneath the rails of both the main and the siding tracks and has free sliding movement at such point. The switch-bar 40 extends out some distance beyond the outer rail 13 of the siding-track B, and a 75 guide-arm 41 is attached to the said switch-bar 40, which guide-arm, as is best shown in Fig. 5^a, is rendered vertical at its outer end 42 and is provided at such end with an aperture 43. The end 42 of the guide-bar 41 has 80 movement in a guide-loop 44, which extends upward from a plate 45, suitably supported, and this plate 45 is provided with standards 46 and 47 parallel with the guide-loop 44. The said standards 46 and 47 of the guide-loop 44 are provided with alining apertures adapted to receive the straight end 48 of a locking rod or bar 48^a, to be hereinafter described, and this locking rod or bar 48^a is brought into action when the switch-points 90 have been shifted to establish communication between the main track and the siding or the siding and the main track, at which time the aperture 43 in the guide-bar 41, connected with the switch-bar 40, is brought into alinement with the apertures in the standards 46 and 47 and the guide-loop 44, so that the straight end 48 of the locking-bar 48^a will at such time not only pass through the apertures in the members of the plate 45, but likewise 95 through the aperture 43 in the guide-bar 41, thereby locking the switch in the position to which it was shifted.

The lever 14, which is operated to shift the switch when a train is to be switched from the 105 main track A to the siding B, is operated by a device controlled by the attendant in the cab of the engine. Such a device is shown in Fig. 6 and consists of a vertical arm 49, having guided movement in bearings located 110 at the pilot of the engine 50. The said trip-arm 49 may be given movement, as is illustrated in Fig. 6, through the medium of an elbow-lever 51, fulcrumed on the framing of the pilot and connected by a suitable link 52 115 with a lever in the cab of the engine. One member of this elbow-lever 51 is shown provided with a slot 53, which receives a pin 54, carried outward from the trip-arm 49, and when the trip-arm is in its lower position, or 120 in a position to engage with the inner end of the lever 14 to operate the same, the trip-arm 49 is held in its lower position by the engagement of a suitable latch 55 on the said arm with a keeper 55^a on the pilot. After the 125 trip-arm 49 has operated on the said lever 14 it is released from its catch and forced upward by engagement with an arched plate 56,

located adjacent to the rail 11 of the main track A and in front of the free end of the lever 14.

The outer end of the switch-bar 40 is pivotally attached to a member of an elbow-lever 57, which is mounted upon a suitable support adjacent to the outer rail 13 of the siding-track B, as is shown in Fig. 1, and a spring 58, attached to this lever 57 and to a suitable support, serves to hold the switch-bar in such position as to normally retain the switch-points C in a position to cause the main track to be normally open.

With reference to the transverse connecting-rod 26 and the lever 27, with which it is connected, the latter being located, as has been stated, adjacent to the outer face of the siding-rail 13, this lever 27, through the medium of a link 59, is pivotally attached to an arm 60, which extends down from one member of a second arched trip-lever D'. This second trip-lever D' is located at the outer face of the siding-rail 13 at a point beyond the fixed frog C, as shown best in Fig. 1. This second arched trip-lever D' consists of two members 61 and 62, of which the member 61 is preferably the longest, and these two members are pivotally connected by a suitable pin 63. In the member 61, from which the arm 60 extends, a longitudinal slot 64 is produced, and a pin 65 is passed through this slot into the outer face of the outer siding-rail 13, while the corresponding end of the shorter link 62 is pivoted directly to the same rail as is illustrated in Figs. 2 and 4.

In the operation of this portion of the improved switch when the trip-arm 49 is lowered as the train approaches the switch by engagement with the free end of the lever, 40 which moves the said lever in direction of the switch, and through the medium of the combined elbow-levers 17 and 19 and the levers 25 and 27 and their connections, the lever 27 is so turned as to draw the end of the trip-lever D' in direction of the switch, carrying said lever from its normal position parallel with the rail 13, as shown in Fig. 4, to an upper arched position corresponding to that of the trip-lever D. (Shown in Fig. 6.) At 45 the same time through the combined action of the connecting-rods 16, 19, and 24 the rocking plate 20 is turned so as to bring its stud 21 against the member 37 of the divided connecting-rod, straightening the said rod and bringing it to the position shown in Fig. 7^a, and as this divided connecting-rod is thus straightened the member a' of the slide 34 connects with the member a of said slide and forces such member in direction of the main 50 operating-lever 14, thus bringing the trip-lever D to the upper arched position. (Shown in Fig. 6.) When the wheels of the engine reach the arched trip-lever D, they force the said trip-lever downward, so that its members are 55 parallel with the rail 11 of the main track,

whereupon through the medium of the slide 34 and the elbow-lever 39 the switch-bar 40 is moved against the tension of its spring 58 and in a direction to carry the switch-points from their normal positions to their shifting positions, establishing communication between the siding and the main track. As the train passes forward and before it reaches the switch by mechanism to be hereinafter described and located adjacent to the outer rail 13 of the siding and outer rail 10 of the main track the switch-points are locked in their shifted position, and the train then passes on to the siding, and when the arched levers D' are reached, the members having 60 been raised as just above described, said members are pressed downward by the wheels passing over them and the locking mechanism is released from the switch-bar and the spring connected with said bar is permitted to act to 65 restore the switch-points to their normal position. At the same time the elbow-levers 27 and 25 are operated upon to operate the rods 24, 23, and 16, restoring the main shifting-lever 14 from the main track to its normal 70 position. At the same time the rocking plate 20 is turned so as to relieve the member 37 of the divided connecting-rod from the pressure of the stud 21, carried by the said plate, whereupon a spring 38^a, connected to one of 75 the members of the said divided connecting-rod and to a fixed support, will draw the members of said rod to the position shown in Fig. 1 at angles to one another, and thus separate the sections a and a' of the plate 34, permitting the arched trip-lever D to be forced down to a position parallel with the rail 10 of the main track when a train passes over said track. 80

With reference to the mechanism employed for automatically shifting the switch-points 85 when a train is to pass from the siding to the main track the construction is as follows: A jointed shifting-lever D² is located adjacent to the jointed trip-lever D'—namely, at the outer side of the outer rail 13 of the siding B, as is 90 best shown in Fig. 2. This shifting-lever D² when pressed downward by the weight of a train passing over the rails is adapted to carry the switch-points in such position as to connect the siding with the main track, whether 95 the train approaches said siding from the main track or approaches the main track from the siding. This jointed shifting-lever D² consists of two links 66 and 67, the link 66 being the shorter of the two, and the link 66 is at 100 what may be termed its "outer" end pivoted to the rail 13 by means of a suitable pin 68, and the two links 66 and 67 are connected by a pin 69. At what may be termed the "outer" 105 or "free" end of the link 67 of the said jointed shifting-lever D² a longitudinal slot 70 is produced, and a pin 71 is passed through this slot into the said rail 13 of the siding B, so 110 that the jointed shifting-lever D² may occupy the arched position (shown in Fig. 2) or the 115

flat position parallel with the rail 13, as is shown in Fig. 3. In fact, the shifting-lever D² is of the same character as the trip-lever D and the trip-lever D', heretofore referred to, and these levers D, D', and D² will be hereinafter designated as "jointed" levers. A connecting-rod 72 is attached to the outer end of the link member 67 of the jointed shifting-lever D², and this rod 72 is pivotally connected with a member of an elbow-lever 73, suitably mounted adjacent to the siding-rail 13, and the elbow-lever 73 is connected by a link 74 with another elbow-lever 75. The elbow-lever 75 is connected by a bar 76 with the bell-crank or elbow lever 57, connected directly with the switch-bar 40, as is clearly shown in Figs. 1, 5, and 5^a. Two slides E and E', the slide E being the inner one, are mounted for end movement at the outer face of the siding-rail 13 and the corresponding rail 10 of the main track A, connecting with the said siding-rail, as is shown particularly in Figs. 4 and 4^a, 5 and 5^a, and likewise in Fig. 1. These slides E and E' have movement in suitable supports 77, connected with the bottom of the rails 13 and 10, or with any supports for said rails. The outer slide E' is provided with a series of longitudinal slots, the slot which is farthest away from the switch and nearest to the jointed shifting-lever D being designated as 78, the next slot as 78^a, the third slot as 79, and the fourth slot as 78^b; but the number of slots in the said slide E' may be varied as required in practice. A pin 80 is attached to the inner slide E, and this pin extends out through the slot 79 in the outer slide E', as is clearly shown in Figs. 4^a and 5^a. A rod 81 is pivotally connected with the pin 80 and with the spring-controlled elbow-lever 57, connected with the switch-bar 40, so that it will be observed that when the jointed shifting-lever D² is pressed downward to throw the switch, which operation may be performed by the train passing over the said shifting-lever D² or by engagement with the operating-lever 14, as the switch-points are thrown the inner slide E is drawn in direction of the said jointed shifting-lever D². A pin 82 is passed from the inner sliding bar E outward through the slot 78 in the outer sliding bar E', and a second pin 82^a is passed from the inner bar E out through the slot 78^a in the outer bar, while a third pin 82^b is passed from the said inner sliding bar E out through the slot 78^b in the outer sliding bar E'. The pin 82 is received by the upper end of a rocking arm 83, the pin 82^a being received by a corresponding arm 83^a, and the pin 82^b is received by the upper end of a third rocking arm 83^b, all of which arms are pivotally mounted in any approved support, as is clearly shown in Figs. 4 and 4^a.

In connection with the jointed shifting-lever D² two correspondingly-formed locking-levers D³ and D⁴ are employed. These locking-levers are adapted to carry the locking member

48 of the locking-arm 48^a to or from engagement with the controlling-bar of the switch-points as the switch-points are to be moved to a shifted position or are to be moved from such position. The locking-lever D³ consists of two links 84 and 85, the link 85 being preferably the shorter, and these links are connected by a suitable pivot-pin 86. The outer end of the longer link 84 is pivotally attached to the outer face of the outer slide E' adjacent to the end which faces the jointed shifting-lever D², and the outer end of the other or shorter link 85 of the said locking-lever D³ is pivotally connected with the pin 82, which passes through the slot 78 in the outer sliding bar E', thus affecting a connection with the inner sliding bar E'. Thus, it will be observed, that one link member of the lock-lever D³ is indirectly connected with the inner slide E, while the other member is directly connected with the outer slide E'. With reference to the lock-lever D⁴, it is of substantially the same construction as the lock-lever D³, being purely a duplicate thereof. This latter lock-lever D⁴, as is shown in Fig. 4^a, consists, for example, of a long link 87, pivotally attached to the outer face of the outer slide E' and a shorter member 88, which is pivotally connected at its outer end with the pin 82^b, which passes through the slot 78^b in the outer slide E' to an engagement with the inner slide E. These link members are connected by a suitable pivot-pin 89.

A spring 90 is attached to the end of the outer slide E', which is carried in direction of the main track A, and the said spring 90 is secured to a support adjacent to the rail 10 of the said main track, as is shown in Figs. 1, 4^a, and 5^a; but the straight portion of the spring 90 passes over a friction-roller 91, suitably located. A stud 92 is projected from the outer face of the outer slide E', where the spring 90 is connected therewith, and the locking-bar 48^a for the switch-bar is attached to this stud in any suitable or approved manner.

The operation of the parts to the right of the main rail—namely, the parts operated by the lever 14—has been described; but in brief it may be repeated that when a train approaches the switch from the main track and is intended to be carried onto the siding B the lever 14 is operated at its free end in direction of the switch, which action throws the switch-points to a position to establish communication between the siding and the main track and at the same time raises the jointed trip-lever D' at the siding-rail to the upper arched position. (Shown in Fig. 6^a.) As the switch-points are shifted to establish such communication between the main track and the siding the jointed shifting-lever D² is drawn down parallel with the siding-rail 13 by the action of the switch-bar 40 passing from one position to the other. At such time the two jointed locking-levers D³ and D⁴ will be raised by

the operation of the jointed shifting-lever D^2 on the inner sliding bar E , causing the said bar to be drawn in direction of the said lever D^2 , and consequently causing the two locking-levers D^3 and D^4 to be carried to an upper elevated position. Therefore after the switch has been shifted by the depression of the jointed trip-lever D^2 the train in its passage to the switch will first strike the nearest lock-lever, which will be the lock-lever D^4 , and will force that lever downward to a position parallel with the track adjacent to which it is located, thus carrying the outer bar E' to a position in direction of the jointed shifting-lever D^2 , and as the bar E' is carried to this position the lock-bar 48^a , connected with the said slide E' , will be carried in the same direction and will pass through the aperture in the guide member of the switch-bar, thus locking the switch-points in place. At the same time the spring 90 is placed under tension. The train will now travel on until it has well passed the switch, and when the wheels of the cars strike the trip-lever D' of the siding and compresses the said lever, as has been stated, it will restore the parts at the right of the main track to their normal position, and as the last wheel of the last car leaves the shifting-lever D^2 the said lever is permitted to rise to its upper or normal position, owing to the spring 58 acting at such time to draw the switch-bar 40 in position to restore the switch-points to their normal place, and at about the same time the spring 90 , connected with the outer sliding bar E' , acts to draw the locking device from engagement with the operative mechanism of the switch-points, permitting the switch-bar 40 to be acted upon by the spring 58 . When a train is on the siding and is to be directed to the main track, the jointed shifting-lever D^2 will be in the position shown in Fig. 2, and the two lock-levers D^3 and D^4 will likewise be in a position parallel with the rail adjacent to which they are located, as shown in Fig. 2^a. As the wheels of the engine, for example, engage with the jointed shifting-lever D^2 the said wheels compress said lever, as is shown in Fig. 3, and cause the lock-levers D^3 and D^4 to be elevated by the sliding action of the slides E and E' , as is shown in Figs. 3 and 3^a. When the jointed shifting-lever D^2 is pressed downward by reason of its connection with the switch-bar 40 , which has been described, the switch-points are drawn to the position to establish communication between the siding and the main track, and as soon as the wheels of the train approach the first lock-lever D^3 said lever is depressed, and the outer slide E' is acted upon in a manner to force the lock-bar 48^a to locking position with the switch-bar 40 , thus holding the switch-points in shifted position, and at the same time by the same action of the slide E' the other lock-lever D^4 is depressed, so that the train passes on until the last wheel

of the train clears the last lock-lever D^4 , whereupon the mechanism just described as brought into action is released and the lock-bar 48^a is carried from locking engagement with the switch-bar 40 , and the jointed shifting-lever D^2 by the automatic return movement of the switch-bar 40 is carried to its normal elevated position. 70

It may here be remarked that the jointed lock-lever D^4 sustains the same relation to the switch when a train is leaving a siding for the main track as does the trip-lever D' when the train is leaving the main track and passes onto and along the siding. 75

Having thus described my invention, I claim 80 as new and desire to secure by Letters Patent—

1. In a switch mechanism, a main track, a siding, and a switch operative with relation to the main track and siding, a jointed shifting-lever located adjacent to the main track 85 and adapted to be operated by a passing train, said shifting-lever adapted to lie parallel with the track in one position and to arch above the track in another position, a connection between said lever and the switch, a locking mechanism for the switch operated by a passing train, and a releasing mechanism for the locking mechanism also operated by a passing train. 90

2. In a switch mechanism, a main track, a siding and a switch operative with relation to the main track and siding, a jointed shifting-lever located adjacent to the main track and adapted to be operated by a passing train, said shifting-lever being adapted to lie parallel with the track in one position and to arch above the track in another position, a connection between said lever and the switch, a locking mechanism for the switch operated by a passing train, a releasing mechanism for the locking mechanism, set by the said operating lever and operated by a passing train, and means for automatically restoring the operating-lever to normal position after the passage of the train onto the siding. 100 105 110

3. In a switch mechanism, a main track, a siding, and a switch operatively mounted with relation to the main track and siding, a tension-controlled operating-bar for the switch, a jointed shifting-lever mounted to lie parallel 115 with a track in one position and to arch above the track in another position, and a connection between the said jointed shifting-lever and the operating-bar for the switch, and a tension-controlled locking device for 120 said operating-bar for the switch, the said shifting-lever and switch-locking device being operated by a passing train. 125

4. In a switch mechanism, a main track, a siding and a switch operatively mounted with 130 relation to the main track and siding, a tension-controlled operating-bar for the switch, a jointed shifting-lever mounted to lie parallel with the track in one position and to arch above the track in another position, link-and-

lever connections between the jointed shifting-lever and the operating-bar for the switch, to move the switch against the tension of the tension device when the shifting-lever is depressed, jointed locking-levers mounted adjacent to the switch, which locking-levers normally occupy a position parallel with the rail of the track, being capable of arching above the rail, a connection between the shifting-lever and the locking-levers, whereby to raise the locking-levers when the shifting-lever is depressed, a tension-controlled locking device for the switch, and means for operating the locking device when the locking-levers are depressed.

5. In a switch mechanism, the combination with the main track, the siding and a switch mounted between the rails of the main track, operative with relation to the said siding, a tension-controlled operating-bar for the switch, a jointed shifting-lever comprising connected members, one of which is pivoted to a rail, the other having sliding connection with the rail, a connection between the said shifting-lever and the operating-bar for the switch, whereby when the shifting-lever is depressed the switch is shifted from normal position, an outer and an inner plate mounted to slide independently adjacent to corresponding rails of the main and siding tracks, a connection between the inner slide and the said shifting-lever, whereby the said inner slide is moved when the shifting-lever is depressed, jointed locking-levers located at the outer slide, each locking-lever comprising two pivotally-connected members, one member being pivoted to the outer slide and the other member being pivotally mounted and having sliding movement relative to the outer slide and attachment to the inner slide, and a locking device for the switch-operating bar connected with the outer slide, being brought into operative position when either of the locking-levers is depressed.

45. 6. In a switch mechanism, the combination with the rails of a main track, the rails of a siding, a switch pivoted between the rails of the main track and having operative relation to the rails of the siding, and a tension-controlled operating-bar attached to the switch-points, of a trip-lever pivoted at an outer rail of the siding, which lever consists of pivotally-connected members, one pivoted to the rail and the other having sliding connection with the rail, an elbow-lever, a connection between the elbow-lever and the sliding member of the trip-lever, a second elbow-lever located adjacent to the outer rail of the main track, a connection between the two elbow-levers, an operating-lever located adjacent to the outer rail of the main track, link-and-lever connections between the operating-lever and the said elbow-lever adjacent to the main track, a trip-lever located at the outer rail of the main track, comprising two pivotally-

connected members, one pivotally connected with the rail and the other having sliding relation to the rail, a slide capable of lost motion connected with the slidably-mounted member of the trip-lever, an elbow-lever connected with the operating-bar of the switch, a tension-controlled connecting medium between the said elbow-lever and the said slide, said medium being in two members pivotally connected, a rotatable plate operated by the links operated from the operating-lever, and an extension from the said rotatable plate, adapted in one position of the plate to engage with and straighten the members connected with the said slide, for the purposes described.

7. In a switch mechanism, the combination with a switch-bar, of a jointed trip-lever, a slide connected with the trip-lever, a bar connected with the slide, and a connection between the bar and the switch-bar.

8. In a switch mechanism, the combination with a switch-rod, of a jointed trip-lever, a two-part slide, a connection between one part of the slide and the trip-lever, a sectional and jointed bar having one section connected with the other part of the slide, a connection between the other section of the jointed bar and the switch-rod, and means for holding the sections of the jointed bar in alinement.

9. In a switch mechanism, the combination with the switch-rod, of a jointed trip-lever, a sectional slide, a connection between one section of the slide and the trip-lever, a sectional and jointed bar having one section connected with the other section of the slide, a connection between the other section of the said bar and the switch-rod, means for holding the sections of the jointed bar in alinement, and means operated by a passing train for controlling the bar-holding means.

10. In a switch mechanism, the combination with a switch-rod, of a jointed trip-lever, a sectional slide, a connection between one section of the slide and the trip-lever, a sectional and jointed bar having one section connected with the other section of the slide, a connection between the other section of the jointed bar and the switch-rod, a fixed stop on one side of one section of the jointed bar, and a swinging member having a projection for engaging the section of the jointed bar opposite which the fixed stop is arranged.

11. In a switch mechanism, the combination with a switch-rod, of a jointed trip-lever, a sectional slide, a connection between one section of the slide and the trip-lever, a sectional and jointed bar having one section pivotally connected with the other section of the slide, an operative connection between the other section of the jointed bar and the switch-rod, means for holding the sections of the jointed bar in alinement, said means comprising a fixed stop and a swinging member, and means controlled by a passing train for operating the swinging member.

12. In a switch mechanism, the combination with a switch-rod, of a jointed trip-lever, a sectional slide having one section pivotally connected with the trip-lever, a sectional and jointed bar having one section pivotally connected with the other section of the slide, an operative connection between the other section of the jointed bar and the switch-rod, a fixed stop at one side of one section of the jointed bar, a swinging member having a projection for engaging the section of the jointed bar opposite which the fixed stop is arranged, a lever adapted to be operated by a passing train, and a connection between the lever and the swinging member.

13. In a switch mechanism, the combination with a switch-rod, of a jointed trip-lever arranged at one side of the main track, an operative connection between the trip-lever and the switch-rod, a lever at one side of the main track and adapted to be operated by a passing train, a second jointed trip-lever arranged at one side of the siding, and a connection between the said lever and the last-named trip-lever.

14. In a switch mechanism, the combination with a switch-rod, of a jointed trip-lever arranged at one side of the main track, mechanism between the trip-lever and the switch-rod for operating the latter from the former, a lever at one side of the main track and adapted to be operated by a passing train, a second jointed trip-lever at one side of the siding, and means for operating the second trip-lever from the said lever, said means controlling the operating mechanism between the first trip-lever and the switch-rod.

15. In a switch mechanism, the combination with a switch-rod, and a spring-pressed elbow-lever for operating the said rod, of a trip-lever formed of two jointed links of unequal length pivoted at their ends at one side of the track, one of the links having a loose pivotal connection, and an operative connection between the trip-lever and the elbow-lever.

16. In a switch mechanism, the combination with a switch-rod, and means for operating the

same, of a guideway, apertured standards at one side of the guideway, an apertured guide-arm secured to the switch-rod and working in said guideway, a locking rod or bar working in the apertures of the standards and adapted to engage the aperture of the said guide-arm, and means for operating the locking-arm.

17. In a switch mechanism, the combination with a switch-rod and means for operating the same, of a guide-arm secured to the switch-arm, locking-arm for engaging the guide-arm, a jointed locking-lever, and means for operating the locking-arm from the locking-lever.

18. In a switch mechanism, the combination with a switch-rod, and means for operating the same, of an arm carried by the switch-arm, a locking-arm for engaging the arm of the switch-rod, a jointed locking-lever, slides to one of which the locking-arm is attached, and a connection between the locking-lever and slides.

19. In a switch mechanism, the combination with a switch-rod, and means for operating the same, of an arm carried by the switch-rod, a locking-arm for engaging the said arm, a jointed locking-lever, slides one of which is spring-pressed and to which the locking-arm is attached, and a connection between the slides and the locking-lever.

20. In a switch mechanism, the combination with a switch-rod having an arm, an elbow-lever connected with the said rod, and means for operating the elbow-lever, of locking-arm for engaging the arm of the switch-rod to lock the same, slides one of which is spring-pressed and to which the locking-arm is attached, a connection between the other slide and the elbow-lever, jointed locking-levers, and connections between the levers and the slides.

In testimony whereof I have signed my name to this specification in the presence of two subscribing witnesses.

CLARENCE E. KLING.
